METHOD AND MEANS FOR TREATING
YARN

Jacob Gottlieb, Gastonia, N. C.

Application July 30, 1931, Serial No. 554,045

3 Claims. (Cl. 117—2)

This invention relates to a method and means for treating yarn so that the yarn can be given a greater amount of twist, that is a greater number of twists per inch, and still so prepare 5 the yarn that it will not kink. Heretofore, the number of turns per inch which can be imparted to yarn in the twisting operation is limited due to the fact that after a certain maximum of turns per inch has been reached, 10 the yarn will kink, thus forming an imperfect product.

An object of this invention is to provide a method and means for treating yarn in the twisting operation by lubricating the yarn thus 15 providing a heavier thread and allowing the use of a heavy traveler to draw in the yarn tauter than has heretofore been accomplished. The weight of the lubricated thread permits more twist to be imparted to the thread without 20 causing the thread to kink. The method is especially adapted for preparing sewing thread.

I am aware that heretofore various methods and means have been employed for the treating 25 of yarn, thread, and the like by subjecting the thread to a bath containing an adhesive or gum, but the primary object of my invention is to subject the yarn prior to the twisting operation to a bath of lubricant to lubricate the thread and therefore to attain the objects enum- 30 erated.

The invention broadly contemplates the passing 35 of strands of yarn into a suitable solution, comprising a lubricant or lubricants in said solution and then drying the yarn by any suitable means such as the passing of the yarn over heated members such as steam pipes and then if desired the yarn can be passed over a suitable support with a positively driven brush for brushing the fibers in alinement with the longitudinal 40 axis of the yarn and then passing the strands of yarn thru the conventional twisting rollers and thru the traveler to wind the thread onto suitable bobbins, after the strands are twisted.

45 By the use of the improved method and means as herein set forth, it has been found that the tensile strength of the thread is increased greatly and that a given length of staple can be used to provide a thread fully 25 per cent stronger 50 than a thread manufactured in the conventional manner from the same length of staple as the lubricant permits greater twist to be imparted to the thread and permits a heavier traveler to set the twist without kinking and the lubricant 55 also causes the fibers to adhere to the out-

side surfaces of the thread to cause the thread to have an appearance similar to that of thread made from single yarn.

Some of the objects of the invention having been stated, other objects will appear as the description proceeds when taken in connection with the accompanying drawings, in which—

Figure 1 is an end view of a twisting frame equipped with means for carrying out my improved method;

Figure 2 is a side elevation of a twisting frame as shown in Figure 1;

Figure 3 is a vertical sectional view thru the tank for supplying the lubricating solution;

Figure 4 is an enlarged cross-sectional view 70 taken thru one side of a twisting frame and showing the means for performing the herein-after explained method;

Figure 5 is an enlarged detail view in elevation showing the mounting for the guide rollers or 75 shafts associated with the steam pipes;

Figure 6 is a cross sectional view taken along the line 6—6 in Figure 5;

Figure 7 is a detail of one end of the rollers 80 or shafts for guiding the thread with relation to the steam pipes.

Referring more specifically to the drawings, the numeral 10 indicates a railway head of a spinning frame having the conventional platform 11 and an end frame 12 with a suitable 85 motor 13 for driving drum 14 for driving the spindles 15 which spindles project thru traveler rings 16 on ring rail 17 with a traveler 18 on each of said traveler rings. The spindles 15 have suitable pulleys 19 thereon over which belts (not shown) are passed from drum 15 for driving the spindles. The spindles are adapted to receive suitable bobbins 21 on which the body of thread 22 is wound, the thread passing from creels 24 supported on the pins 25 mounted on supports 26 on creed frame supports 27. The spinning frame is also equipped with guides 29 and feed rollers 30 and 31.

The above described parts are conventional and cooperating with these parts are the other features of the means for performing the method herein-after explained. These features are the providing elongated troughs 40 on each side of the twister supported by any suitable means such as supports 42, and these troughs extend upwardly and outwardly as at 43 to a greater extent than to the troughs heretofore used.

I provide a bracket 45 secured to vertical supports 27 on each side of the frame in which I secure a shaft 46 and on shaft 46 at spaced

intervals, I secure supports 48 by any suitable means such as a set screw 49. These supports 48 serve not only to support the rod or roller 50 for causing the strands of yarn 51 and 52 5 to be submerged in the lubricating solution 54, but these brackets also support rollers or rods 55 and 56 which rollers or rods are mounted in suitable slots 57 and 58 respectively, and are adjustably secured in said slots by means of 10 bearing members 59 being adjustably secured by nut 60, threadably engaging the bearing which penetrates the slot and into which the bearing portion 61 of rods or rollers 55 or 56, as the case may be, are adapted to fit.

15 Each of brackets 48 has a downwardly projecting portion 63 which rests on the bottom of trough 40 for assisting in the supporting of said brackets. Said brackets also have secured therein steam pipes 65 and 66, the pipe 66 being 20 connected to a pipe 67 leading from a source of steam supply and after pipe 66 traverses the entire length of its respective trough, it is bent upon itself and led back to the other end of the trough, the lower portion being indicated 25 by reference character 65. Pipe 65 is led from the end of the trough and is connected to a pipe 69 which leads to a suitable trap or other exhaust means.

30 Mounted on top of the railway head or in any other suitable position is a tank 70 which is shown open at its upper end, but which may be covered if desired. A Pipe 71 leads from steam supply pipe 67 thru tank 70 in the form of a coil 72 and has exhaust pipe 73 which is 35 led to any suitable trap or other conventional means for regulating the passage of steam thru coil 72. The purpose of this arrangement is to heat the lubricant to break down said lubricant and to cause it to adhere to and penetrate the 40 yarn. A pipe 75 is led from near the bottom of tank 70 and has branches 76 and 77 having suitable valves 78 and 79 therein for regulating the flow of fluid from tank 70 into the troughs 45 40. In the other ends of troughs 40 upper and lower pipes 80 and 81 penetrate the end wall of each of said troughs with pipe 81 having valve 82 therein which may normally be closed or opened any desired amount, and these pipes 50 80 and 81 are connected to a pipe 84 which leads to one side of a pump 85 driven by any suitable means such as an electric motor 86 and from the other side of pump 85 a pipe 87 is led beneath the machine and empties into tank 70 as at 88. It is thus seen that lubricant is heated 55 and poured into one end of the tanks and is withdrawn as fast as desired from the other end of the tanks normally into overflow pipe 80 and also into a pipe 81 if desired and is passed thru pump 85 where it is broken up and passed 60 on into tank 70 where it is again heated and thus the lubricant is supplied to the trough of the proper temperature to properly penetrate and adhere to the strands of yarn as they are passed beneath rod or roller 50.

65 If desired, I can provide suitable supports 90 as shown in Figure 4 but omitted in Figures 1 and 2 for supporting member 91 across which the thread is passed, and a brush 92 may be mounted above support 91 extending all the 70 way across the machine and which is positively driven from the machine by means, not shown, the direction of rotation being indicated by the

arrow in Figure 4 and when this brush is used it will aid in the alinement of the fibers which project from the yarn to cause them to stick to the yarn to render the yarn smoother and stronger than heretofore, and when the strands of yarn are passed on into the twisting operation, the rollers 30 and 31 will assist in setting the surface fibers into the surface of the yarn and in this position the surface fibers will assume a position which is parallel to the longitudinal axis of the thread.

80 It is thus seen that by use of the above means the yarn can be treated to provide a thread to which a greater amount to twist can be imparted without kinking, thus permitting a heavier traveler to be used to draw the thread on bobbin 22 tauter than has heretofore been possible, thus setting the twist and eliminating the possibility of any kinks due to the use of the lubricant, and thus providing a thread much stronger and smoother from a given length of staple than has heretofore been possible.

90 Any suitable lubricating bath may be used, but I have found that a solution of 150 pounds of paraffin wax, 40 pounds of white tallow, one pound of soda ash, 30 pounds of rosin mixed with a solvent, or a like amount of triethanolamine, with enough water added to make a solution of 50 gallons is suitable in carrying out my method, though it is evident that the ingredients of the bath may be varied to suit individual requirements.

95 In the drawings and specification there has been set forth a preferred embodiment of the invention and although specific terms are employed, they are used in a generic and descriptive sense only and not for purposes of limitation, the scope of the invention being set forth in the appended claims.

105 I claim:

1. In a twisting frame having a plurality of supports for packages of yarn and having a vat adapted to contain a treating solution with a member mounted in said vat under which the strands of yarn are passed, a plurality of brackets, a plurality of steam heated pipes mounted in said bracket, means adjustably mounted in said bracket for directing the yarn selectively against said heated pipes, a brush 120 adapted to be positively driven by the machine for brushing the strands of thread after they have passed over the steam heated pipes, and means for directing the strands of yarn to the twisting means.

125 2. Means for treating yarn in a twisting frame prior to the twisting operation comprising twisting means, a vat having a treating solution therein, a plurality of steam heated pipes disposed in close proximity to the treating solution, 130 means for selectively directing the strands of yarn to engage selectively the steam heated pipes as the strands pass the pipes while moving to the twisting means and means for wiping the strands of thread before the twisting operation.

140 3. That method of treating cotton yarn comprising subjecting the yarn to a bath comprising a solution of paraffin, tallow, soda ash, rosin and a solvent for the rosin, partially drying the yarn and then twisting the yarn.
